CLOSURE PLUG FOR A BALLPOINT REFILL OR THE LIKE

Robert John Darst, Fort Madison, Iowa, assignor to
Textron, Inc., Providence, R.I., a corporation of Rhode
Island

Filed May 24, 1965, Ser. No. 85,427

Term of patent 14 years

(Cl. D74—17)

FIGURE 1 is a perspective view of a closure plug for a ballpoint refill or the like showing my new design, the refill unit itself being shown in dotted lines with portions broken away for illustrative purposes only;

FIG. 2 is an enlarged side elevational view of the closure plug for a ballpoint refill or the like embodying my new design;

FIG. 3 is an enlarged end elevational view of the design;

FIG. 4 is an enlarged top plan view thereof; and

FIG. 5 is an enlarged bottom plan view thereof.

I claim:

The ornamental design for a closure plug for a ballpoint refill or the like, substantially as shown and described.
